UNITED STATES PATENT OFFICE.

ORLO RICE, OF DETROIT, MICHIGAN.

PRIMING CUP.

Application filed March 22, 1923. Serial No. 626,971.

To all whom it may concern:

Be it known that I, ORLO RICE, a citizen of the United States of America, residing at Detroit, in the county of Wayne and State 5 of Michigan, have invented certain new and useful Improvements in Priming Cups, of which the following is a specification, reference being had therein to the accompanying drawings.

10 This invention relates to priming cups and it is the object of the invention to provide a priming cup having two valve members under a common control for closing the discharge passage of the cup whereby any loss 15 of gas pressure through the priming cup is very positively prevented.

In the drawings:—

Figure 1 is a view in side elevation and partial section of the improved cup;

20 Figure 2 is a similar view of an alternative construction;

Figure 3 is a cross section on line 3—3 of Figure 2.

In these views, the reference character A 25 designates the base or supporting member of the cup and B the cup proper which has detachable engagement with said base. The member A is formed with the central discharge passage a^3 and comprises exteriorly 30 threaded end portions a and a' for respective engagement with an engine casing (not shown) and by the cup member B and comprises further the intermediate polygonal nut portion a^2 . The member B has the cup 35 forming depression b^2 in its upper portion and has its lower portion reduced in diameter and formed with the interiorly threaded opening b^3 for engagement with the part a' of the base A. Said opening is adapted 40 to communicate with the cup b^2 by a port b which is located substantially midway of the height of the cup member B which registers with the passage a^3 and port b , said stem having an integral conical valve member D upon its lower end adapted to seat upon 45 the lower end of the base A and carrying at its upper end the detachable valve member E adapted to seat within the cup opening b^2 marginally of the port b . While the 50 member E may be variously connected to the stem C, the construction shown provides said valve member with a threaded shank F adapted to be engaged in a tapped opening in the upper end of the stem C. G is a pin 55 mounted in a transverse bore of the stem C

and clamped fast to said stem by the shank F, said pin projecting sufficiently at each end above the portion a' of the base, the upper end portion of the opening b^3 accommodating the projecting ends of said pin. 60

In the use of the described priming cup, the two valves D and E are adapted to be firmly engaged with their respective seats by screwing the cup member to raise the same relative to the base. When said valves 65 are seated, the pin G is spaced slightly above the upper end of the base as Figure 1 illustrates. To unseat said valve members and open the port B and passage a^3 for a discharge of priming fuel from the cup b^2 , 70 the member B is rotated to screw the same downwardly upon the base A. The initial effect of such an adjustment is to unseat the valve D and bring the pin G to bear upon the upper end of the base A. A continued 75 turning of the member B then acts to unseat the valve E.

In the alternative construction shown in Figures 2 and 3, a disk element H fast upon the stem h' is substituted for the pin G 80 shown in Figure 1, said disk being cut away as indicated at h^2 at opposite sides thereof to allow for a flow of the priming liquid downwardly past said disk. A further feature of this modification lies in the forming 85 of both the lower and upper valve members J and J' respectively separately from the stem h' and establishing a screw threaded connection between said valve members and the stem. The reduced extremities h^3 of the 90 stem which establishes this connection are preferably riveted over upon the valve members as indicated at h^4 to maintain a permanent assembly of the stem and valve members. 95

It is a feature of both forms of the described invention that the rapidity with which heat is dissipated to the atmosphere from the priming cup is increased by forming the upper member B of the cup with 100 one or more annular grooves K between which narrow ribs K' are formed. Increasing the rapidity of heat radiation is desirable as under some conditions, the priming cups tend to become so hot that they may not 105 safely be grasped with the bare hand for effecting control.

In its preferred form herein shown and described my improved test or priming cup, although particularly constructed for use 110

with internal combustion engines, is of course adapted to be used for various other purposes.

What I claim as my invention is:—

- 5 1. In a priming cup, a discharge passage for a priming liquid, and control means for said passage adapted to close the same at two separate points.
- 10 2. In a priming cup, a discharge passage for a priming liquid, and means under a common control for closing said passage at two separate points thereof.
- 15 3. In a priming cup, a discharge passage having valve seats at two spaced points thereof, valves respectively engageable with said seats, and a common means for seating or unseating both valves.
- 20 4. In a priming cup, a discharge passage having reversely facing valve seats at two spaced points thereof, valves respectively engageable with said seats, and a common means for seating or unseating both of said valves.
- 25 5. A priming cup comprising a body having a discharge passage for the priming liquid and comprising two parts, of valves controlling said passage and adapted to respectively seat upon said parts, and a stem connecting said valves, said parts being relatively movable longitudinally of said passage to seat or unseat said valves.
- 30 6. A priming cup comprising upper and lower parts having a discharge passage extending through both parts thereof, said parts being relatively movable longitudinally of said passage, valves respectively adapted to seat upon said parts for controlling said passage, a stem extending through said passage connecting said valves, and a projection upon said stem engageable with the lowermost part to limit lowering of the two valves resulting from lowering of the uppermost part whereby the lower valve member is shifted from its seat in the opening movement thereof, and the upper valve is opened by shifting the seat forming member from the valve.
- 35 7. A priming cup comprising a supporting lower member and a cupped upper member, said members having a screw threaded engagement and together forming a discharge passage for a priming liquid, a stem extending within said passage, valves terminally carried by said stem reversely seating upon said upper and lower members to control said passage, seating of said valves being effected by screwing the cup

forming member upwardly upon the supporting member.

8. A priming cup comprising a body having a discharge passage for the priming liquid, of reversely seating valves controlling said passage at opposite ends thereof, a stem connecting said valves extending through said passage, means for relatively adjusting the valves and their seats, and a projection upon said stem seating upon said cup and limiting the opening movement of the lower valves.

9. A priming cup comprising a body having a discharge passage for the priming liquid and comprising two parts, of valves controlling said passage and adapted to respectively seat upon said parts, said parts having screw threaded engagement providing for a relative movement thereof longitudinally of said passage to control both of said valves.

10. A priming cup comprising a body having a discharge passage for the priming liquid and comprising two parts respectively having valve seats, of valves controlling said passage and respectively engageable with said seats, and a stem connecting said valves through said passage, said parts having screw threaded engagement provided for a relative movement longitudinally of said passage to control said valves.

11. A priming cup comprising a body having a discharge passage for the priming liquid, said body comprising upper and lower parts, of valves controlling said passage and adapted to seat upwardly upon one of said parts and downwardly upon the other, a stem connecting said valves, and means upon said stem between said valves engageable with one of said parts subsequent to opening of the upwardly seating valve to effect opening of the downwardly seating valve, responsive to relative longitudinal movement of the parts.

12. A priming cup comprising a body having upper and lower parts, said body having a discharge passage for a priming liquid, of a valve seating upwardly upon one of said parts, a valve seating downwardly upon the other parts, the upwardly seating valve and downwardly seating valve being successively actuatable to open position through relative longitudinal adjustment of said parts.

In testimony whereof I affix my signature.

ORLO RICE.
